UNITED STATES PATENT OFFICE.

DANIEL LYNCH, OF MINERVA, NEW YORK.

CAR-STARTER.

SPECIFICATION forming part of Letters Patent No. 369,116, dated August 30, 1887.

Application filed December 18, 1886. Serial No. 221,948. (No model.)

To all whom it may concern:

Be it known that I, DANIEL LYNCH, of Minerva, in the county of Essex and State of New York, have invented a new and Improved 5 Car- Starter, of which the following is a full, clear, and exact description.

My invention relates to car-starters, and has for its object to provide a simple and effective apparatus of this character, which may be 10 readily controlled by the driver at either end of a car, and so as to start the car either forward or backward, as may be required.

The invention consists in certain novel features of construction and combinations of 15 parts of the car-starter, all as hereinafter fully described and claimed.

Reference is to be had to the accompanying drawings, forming a part of this specification, in which similar letters of reference indicate 20 corresponding parts in all the figures.

Figure 1 is a vertical longitudinal sectional elevation of the lower part of a street-railroad car with my improved car-starter attached. Fig. 2 is a bottom plan view of the same. Fig. 25 3 is a detail perspective view of the principal parts of the car-starter mechanism. Fig. 4 is a detail perspective view showing the connection of the spring-tension band with the barrel on one of the friction-wheel shafts; and Fig. 5 is a vertical sectional elevation of the 30 starter-spring, its barrel or case, and attached ratchet-wheel.

The car-body A is supported on wheels B C, fixed to axles b c, journaled in boxes b' c', respectively, on the car-frame.

To the axle b of the wheels B there is fixed a friction-drum, D, against which friction-wheels E F, fitted in a frame, G, are adapted to act. This frame G is pivoted at points adjacent the meeting peripheries of the wheels E F in hangers or brackets H, fixed to the car-frame or convenient support, allowing either of the wheels E F to be brought into contact with the drum by swinging the frame on its 40 pivots. The upper friction-wheel, E, is journaled directly in the side bars of the frame G, and the lower friction-wheel, F, is journaled in boxes f, which are adapted to move in vertical slots made in the frame, and screws f', threaded into the frame, provide a means of pressing the wheel F against the wheel E, to

assure turning of one of the wheels by the other when either wheel is turned by the drum.

On the shaft e of the friction-wheel E there is fixed a barrel, I, to which is connected one end 55 of a band or belt, J, the other end of which is secured to the periphery of a case or barrel, L, within which a coiled spring, K, is fitted. The case L is journaled on a shaft, l, fixed in a hanger, M, pendent from the car-body. One end of 60 the spring K is fixed to the shaft l, and its other end is fixed to the case L, which has fixed to it a ratchet-wheel, N, with which a dog, O, pivoted in a hanger fixed to the car-body, is adapted to engage to prevent unwinding of the spring 65 until the dog is tripped by devices presently described. The connection of the band J with the barrel I at j is such as will allow the band to wind in either direction on the barrel. (See Fig. 4 of the drawings.)

To the top of the pivoted friction-wheel frame G there are connected two rods, P R. The rod P extends to one end of the car, and is connected pivotally with a lever-socket, S, at a point above the fulcrum e of said socket, 70 and the rod R extends to the other end of the car, where it is connected pivotally with a lever-socket, T, at a point below the fulcrum t of said socket. These oscillating sockets S T are pivoted or fulcrumed in suitable brackets 75 or hangers fixed beneath the outer parts of the car-platforms a a', respectively, and are adapted to receive a lever-bar, U, which may be transferred to either socket to be handled by the driver of the car, and because of the connection of the rods P R to the respective sockets S T, above and below the pivots of the sockets, the same movements of the lever at either end of the car will have like effects in swinging the frame G for controlling the contact of the 80 friction-wheels E F with the axle-drum D, as presently explained.

The dog or pawl O has an upwardly-projecting tail-piece or stem, o, which stands between lugs v v on a bar, V, which is fitted to slide 95 in lug-bearings v' v', fixed to the car-body, and chains W X, fixed to opposite ends of the bar V, extend to opposite end platforms of the car, and are connected to reversely-arranged elbow-levers Y, which are fulcrumed to the car-frame, 100 and are adapted to be turned by downward movement of plunger-rods Z, which are fitted

for vertical sliding movement in the car-plateforms, and are normally forced upward by springs z , acting between foot-plates attached to the levers and the platforms.

5 A suitable casing, a' , is provided for covering up the lever-socket and adjacent plunger-rod at the rear end of the car, while the lever U is adjusted in the socket at the front or opposite end of the car. The casing a' prevents 10 the accidental or malicious operation of the lever-socket and plunger-rod which it covers.

The operation is as follows: I will suppose the car is adjusted for traveling forward in direction of arrow 1 in Fig. 1 of the drawings. When it is necessary to stop the car, the driver on the platform a will push the lever U in socket S from him. This will swing the frame G and carry the lower friction-wheel, F , against the friction drum D , which is rotating 15 in direction of the arrow 2, and thereby cause the friction-wheel E to turn in like direction and turn the barrel I , fixed to its axle e , thereby winding the band J on the barrel and putting the spring K in tension to store up power, and 20 the dog O will engage the ratchet N , to prevent recoil of the spring. The friction induced by the contact of the wheel F and drum D and the resistance offered by the spring K will together operate as a brake to stop the car, while 25 the power for starting the car is at the same time stored up in or by the spring. When the car is to be started, the driver will press down the plunger Z with his foot as he starts the horses, and this movement will operate the elbow-lever Y to draw on the chain W and bar V and trip the dog O from the ratchet-wheel N on the spring-barrel L , thus 30 releasing the spring K , and just prior to depressing the plunger, or about at the same time, the driver will pull the lever U toward him, which will bring the friction wheel E in contact with the car-axle drum D , so that as 35 the spring K recoils the band J will be rewound onto the spring-casing L and will be unwound from the barrel I , and the direct pressure of 40 the wheel E on the drum D will turn the axle b and car-wheels B forward, and thereby start or assist in starting the car. If in starting the car it is desired to back it, the recoil 45 of the spring K may be utilized to effect this by holding the lever to keep the friction-wheel F in contact with the drum D , and whereby, as the released spring turns the barrel I and wheel E , the wheel F will have effect to turn 50 the drum D and wheels B backward to back the car. When the driver stands on the other end platform, a' , of the car, which is then traveling in direction of the arrow 3, the lever U , then set into the socket T , will be pushed outward 55 to bring the friction-wheel F in contact with the friction-drum D to stop the car and put the spring K in tension, and a reversal of movement of the lever when the dog O is tripped by depressing the plunger Z at the 60 platform a' will carry the wheel E against the drum D , to utilize the recoil of the spring for starting the car. It will be understood that

as the car-wheels B and drum D now move in direction of the arrow 4 the band J will be wound upon the barrel I from its under side 70 or face when the spring is put in tension, instead of from its upper side, as it does when the car is traveling in the other direction. When the car is moving in direction of the arrow 3, it may be started backward by simply 75 holding the lever B to continue the contact of the friction-wheel F with the drum D in substantially the same manner as when the car is moving the other way. As the band J may wind upon the barrel I in both directions, it 80 is obvious that the car will be started forward in either direction by bringing either of the friction-wheels E F into contact with the axle-drum D , and then reversing the motion of the lever U to bring the other of the two friction-wheels into contact with the drum.

The importance of arranging the lever-sock- 85 ets or levers ST , with their fulerums, one above and the other below the points of connection with them of the rods which vibrate the friction-wheel frame will be understood when it is considered that this arrangement allows or causes the same movements of the lever-sock- 90 ets and lever at either end of the car for starting the car forward or backward when trav- 95 eling in either direction; hence a driver of ordinary intelligence may without confusion of thought or action operate the mechanism to apply the brake and to start the car.

It is obvious that the starter mechanism, in- 100 cluding the friction drum and wheels and a device for storing up power as the car is stopped, may be applied to "bob-tail" cars traveling usually in one direction, and in this case the rod, chain, and lever-connections will 105 extend to one end of the car only.

Parts of my invention are adapted for use with devices other than a spring connected to one of the friction-wheels and adapted to store power by contact of one of the friction-wheels 110 with the drum in stopping the car.

Having thus described my invention, what I claim as new, and desire to secure by Letters Patent, is—

1. In a car starter, the combination, with a 115 car-axle and a drum thereon, of a pivoted frame adjacent to the drum, friction-wheels journaled in the said frame and in frictional contact, a barrel on the axle of one of the friction-wheels, a spring-casing suspended from 120 the under side of the car, a band connected to the said casing and to the barrel on the friction-wheel, and means for operating the pivoted frame and for holding and releasing the spring-casing, substantially as herein shown and de- 125 scribed.

2. In a car-starter, the combination, with a 130 friction-drum fixed on one of the car-axles, of a frame centrally pivoted about in the plane of the axle, two friction-wheels journaled in the frame and in frictional contact, a barrel on the axle of one wheel, a spring-case pro- 135 vided with a ratchet and dog, a band connected to said case and to the barrel on the

friction-wheel axle, a lever at each end of the car, and connections from said levers to the friction-wheel frame, a tripping device for the dog, and devices for operating the tripping device from either end of the car, all constructed and arranged for operation substantially as herein set forth.

3. In a car-starter, the combination, with the car-axle *b*, of a drum, *D*, fixed thereto, a frame, *G*, pivoted to the car next the drum, friction-wheels *E F*, journaled in said frame and in frictional contact, a barrel, *I*, on the axle of the wheel *E*, a spring device, *K L*, and ratchet *N*, a dog, *O*, engaging said ratchet, a band, *J*, connected to the barrel *I* and spring-casing *L*, a lever, as *S U*, fulcrumed on the car, a rod, as *P*, connecting said lever to the frame *G*, and a device for tripping the dog to release the spring *K*, substantially as described, for the purposes set forth.

4. In a car-starter, the combination, with the car-axle *b*, of a drum, *D*, fixed thereto, a frame, *G*, pivoted to the car next the drum, friction-wheels *E F*, journaled in said frame and in frictional contact, a barrel, *I*, on the axle of wheel *E*, a spring device, *K L*, and ratchet *N*, a dog, *O*, engaging said ratchet, a band, *J*, connected to the barrel *I* and spring-case *L*, a lever, as *S U*, fulcrumed on the car, a rod, as *P*, connecting said lever to the frame *G*, a bar, *V*, fitted to trip the dog from the ratchet, an elbow-lever, *Y*, pivoted to the car, a chain, *W*, connecting the elbow-lever to the bar *V*, and a plunger, *Z*, connected to the 35 elbow-lever and adapted when depressed to trip the dog *O* from the ratchet *N*, substantially as described, for the purposes set forth.

5. In a car-starter, the combination, with the car-axle *b*, of a drum, *D*, fixed thereto, a frame, *G*, pivoted to the car next the drum, friction-wheels *E F*, journaled in said frame and in frictional contact, a barrel, *I*, on the axle of wheel *E*, a spring device, *K L*, and ratchet *N*, a dog, *O*, engaging said ratchet, a 45 band, *J*, connected to the barrel *I* and spring-

case *L*, a lever-socket, *S*, fulcrumed at one end of the car, a rod, *P*, connecting said socket above its fulcrum *s* with the frame *G*, a lever-socket, *T*, fulcrumed at the other end of the car, a rod, *R*, connecting said socket below its fulcrum *t* with the frame *G*, a bar, *V*, fitted to slide on the car and provided with lugs *v v*, adapted to trip the dog *O*, chains *W X*, connected to opposite ends of the bar *V*, elbow-levers *Y Y*, fulcrumed at opposite ends of the car, and plungers *Z Z*, connected to the levers *Y Y*, and adapted when depressed to trip the dog *O* from the ratchet *N*, substantially as shown and described.

6. In a car-starter, the combination, with the car-axle *b*, a drum, *D*, fixed thereto, a frame, *G*, pivoted to the car next the drum, friction-wheels *E F*, journaled in said frame and in frictional contact, and lever-sockets or levers, as *S T*, fulcrumed at opposite ends of the car, of rods *P R*, connecting said parts *S T* at points above and below their fulcrums *s t*, respectively, with the oscillatory frame *G*, substantially as shown and described, whereby the same movements of the lever-sockets or levers will have like effect in swinging the frame to set its friction-wheels to the axle-drum, as set forth.

7. In a car-starter, the combination, with a friction drum and wheel mechanism adapted to stop the car by contact of a friction-wheel with the axle-drum, and a spring-tension device, as at *K L*, a ratchet, *N*, connected thereto, and a dog, *O*, engaging the ratchet, of a bar, *V*, having lugs *v v*, adapted to trip the dog from the ratchet as the bar is moved endwise, and connections from opposite ends of the bar *V* to a plunger or treadle device at each end of the car adapted to trip the dog when depressed by the driver, substantially as shown and described.

DANIEL LYNCH.
